CONTROL ARRANGEMENT FOR TANDEM
OPERATION PRESSING MACHINESEdwin A. Mall, Norwood, Ohio, assignor to The
American Laundry Machinery Company, Cin-
cinnati, Ohio, a corporation of Ohio

Application August 24, 1933, Serial No. 686,561

1 Claim. (Cl. 68—9)

This invention relates to pressing machines and, particularly, to an arrangement of a plurality of pressing machines for tandem operation and to control mechanism for such machines.

Tandem operation of pressing machines is well known in the art, the primary purpose of tandem arrangement being to save the time of the operator in keeping a plurality of pressing machines simultaneously in operation. In a usual arrangement of machines in tandem, two machines of standard construction and arrangement of parts are placed at right angles to each other as, for instance, with the right front corner of one

10

pressing machine table joining the left front corner of the other table.

The pressing machines are, as hereinbefore stated, usually of standard design with each machine embodying two-hand control means which necessitates the use of both of the operator's hands to bring about operation of the pressing machine. Such controls are usually placed one on each side of the center of each table and one control of each press is connected with a tandem valve for causing release of the second press, so that actuation of the control to close the first press causes opening of the second press.

Likewise, the pressing elements of these machines are usually arranged in the standard position, for instance, with the narrower end of the usual elongated and tapering pressing bed or buck of each press at the same side of the press, for example, with the narrower end of each pressing bed at the right hand end of the machine. A major portion, probably 75 per cent or more, of laundry work is pressed on the smaller end of the bed. Therefore, with such a tandem arrangement, after arranging a garment the operator is required to move from the right hand end of one press to the center of that press to operate its controls, thence to the right hand end of the other press to remove a pressed garment therefrom and to arrange another garment thereon for pressing, and thence to the center of the second press to operate its controls.

One object of my invention is to provide an arrangement of a plurality of pressing machines which reduces the distance travelled by the operator. This is accomplished by placing the machines with the narrower ends of the tapered pressing elements adjacent each other, and by arranging the controls of each machine near this common point.

Another object of my invention is to provide a control mechanism wherein a single control member has a press-opening effect at one ma-

chine and, simultaneously therewith, a press-closing effect at another machine.

Various other objects and advantages of my invention will be apparent from the following description, together with the drawings, in which, Fig. 1 is a perspective view of two presses arranged in tandem formation in accordance with my invention; Fig. 2 is a view showing a control member common to two machines; and Fig. 3 is a diagrammatical view of the operating parts of Fig. 1 showing the tandem relation of the operating parts and controls of the two machines.

While my improved tandem arrangement and control mechanism may be used with any type of press, I have chosen to illustrate the same as applied to presses of the type illustrated, described and claimed in the copending application of John P. Singiser, Serial No. 642,053, filed November 10, 1932. I will therefore give a sufficient description of the operating parts of such a press to permit an understanding of the present invention, reference being had to the above-mentioned application for further details, if desired.

The invention is illustrated in Fig. 1 as applied to two presses, A and B, arranged substantially at right angles to each other for joint operation by one operator. Press A shows the pressing elements in a position just prior to the final pressing operation. Press B shows the pressing elements in open position.

The pressing elements of press A are shown in position with the narrow end of the elements toward the right side of the machine. Pressing elements of press B are shown with the narrow end of the pressing elements toward the left side of the machine. Thus the presses as they are arranged have their smaller ends adjacent. In laundry practice the greater proportion of the garments are drawn over and pressed on the smaller end of the buck. Thus in operation, the operator stands near the intersection of the two presses or in other words in a position where the fewest steps are required to handle work on and off the pressing beds of both machines.

The control levers 10 and 11 of press A are shown in position depressed by the operator to lower the pressing head. The tandem valve 12 is mounted on a bracket 13 in a position such that the depressing of the lever 10 opens this valve which admits air to a release cylinder 17 mounted at the base of the press B and causes the release mechanism connected with treadle 18 of the press B to be actuated and the press-

ing elements of that press to be moved to open position.

The press B is provided in similar fashion with two levers 14 and 15. Lever 14 is provided in the same manner as lever 10 with a tandem valve 16 which is actuated when the control lever 14 is depressed and admits air to a tandem cylinder 17a identical with that used on press B which actuates the mechanism connected with release treadle 18a and opens the pressing elements of press A.

It will be noted that the presses of Fig. 1 are arranged angularly with respect to each other and that the control levers are positioned on the side of the longitudinal center of each press toward the vertex of the angle.

Control 11 is in series with control 10 and air does not enter its valve until control 10 is operated. Likewise on press B control 15 is in series with control 14 and it likewise is second in the series and the air does not pass through it until 14 is operated. Thus, if it is so desired, the controls 11 and 15 may be combined into one control. A simple manner of doing this is shown in Fig. 2 where the controls are linked together by a link 19, although it will be apparent the controls might be redesigned and placed in one structure.

The power means and control mechanism of press A are identical in construction with that of press B and will be described in connection with press B only, similar parts on press A being similarly numbered, with the addition of the suffix *a*.

Referring now to Fig. 3, the power operating means comprises a cylinder 20, having a suitable piston 21, and a piston rod 22 operatively connected to the toggle members of the press, not shown. A valve casing 23 is mounted on top of the cylinder and contains a piston valve 24 adapted to move backward and forward to close the inlet port 25 in the forward position and the exhaust port 26 in rearward position.

The inlet port is connected by a conduit 27 to a source of fluid pressure supply 28 through valves 29 and 30, connected in series by suitable conduits. Valves 29 and 30 are operable by controls 14 and 15 respectively. The exhaust port 26 lies between the passage 31 of the cylinder and a muffler 32. The piston valve 24 is provided with small holes 33 in the periphery of its cup such that when air is admitted through the port 25 the valve is forced against the exhaust port and, at the same time, fluid pressure is directed through the holes and the passage 31 to the cylinder. Another valve 34 is mounted on the cylinder and is connected directly to the main fluid pressure supply. This valve is operated by the rearward movement of the piston 21. For this purpose a bar 35 is attached to the piston rod and operates through a guide in the rear of the cylinder. The forward end 36 of the bar for a short distance is of narrower width than the remainder such that when the piston travels to the rear, the narrower portion allows a bell crank lever 37 to rotate on its pivot 38 and opens the valve 34. When the cutaway portion of the rod 35 has reached the position as described above, the piston through its connection with the toggle members of the press has caused the press head to lower into contact with the bed. Thus, when the valve 34 is opened, it directs the fluid pressure in the main supply through conduit 34' directly to the head of the piston and seals the pressing elements in their pressing po-

sition. Up to the time that the cutaway portion of bar 35 engages the bell crank 37, it is necessary for the operator to maintain the control levers 14 and 15 in a depressed condition to admit fluid pressure to the cylinder 20. Thus both hands of the operator are occupied until the pressing elements are in contact. Then, upon operation of the valve 34 as just described the operator may release the control levers 14 and 15 and fluid pressure on the piston will be maintained.

To release the pressure and raise the press head, the operator may step on the foot treadle 18. The foot treadle is provided with an upwardly extending portion 39 adapted to engage a bell crank lever 40 above its pivot point so that it is rotated in a counterclockwise direction. A link 41 connects one arm of the bell crank 40 with an arm of a bell crank 42. The counterclockwise movement of the bell crank 40 pulls 20 downwardly on link 41 and rotates bell crank 42 in a counterclockwise direction. The vertical arm of bell crank 42 is adapted to engage a cam surface 43 of the lever 37 and to rotate lever 37 in a counterclockwise direction which relieves 25 the pressure of the arm 44 on the stem of valve 34. This operation closes the valve 34. Simultaneously the extreme upper portion of the vertical arm of bell crank 42 engages a push-rod 45 and moves it forward or to the left in Fig. 3. 30 The rod 45 engages a post on the piston valve 24 and moves it away from its engagement with the exhaust port 26 and the fluid pressure is relieved through the passage 31, the exhaust port 26 and muffler 32 to the atmosphere.

The release operation of the press may also be accomplished by means of a tandem valve, arranged to be actuated with movement of the control member of another press in press-closing direction. Thus a tandem valve 12 on press A 40 is arranged to be opened by depression of control member 10, when that member is actuated to close press A. Opening of valve 12 admits fluid pressure from a suitable source through conduit 47 to release cylinder 17 of press B. This 45 release cylinder has a piston 48 and plunger 49 adapted to move bell-crank 40 in counterclockwise direction, to cause opening of press B in the same manner as described in connection with the depression of treadle 18.

The tandem operation of the presses is as follows: The operator arranges the lay of the work on press B and depresses controls 14 and 15. Fluid pressure flows from the main supply line 28 through valves 29 and 30, conduit 27, and 55 port 25 in valve casing 23.

Piston valve 24 is moved against the exhaust port 26 and fluid pressure is directed through passage 31 to the head of the piston 21. The piston moves rearwardly or to the right in Fig. 3. 60 When the cutaway portion 36 of the bar 35 has reached the roller of the lever 37, the lever rotates clockwise and opens valve 34. Fluid pressure is now directed from main supply 28 through open valve 34 and conduit 34' to the head of the 65 piston. Fluid pressure is thereby maintained against piston 21 and the operator's hands may be removed from the control levers 14 and 15. Simultaneously with the operation of depressing the lever 14, the tandem valve 16 is opened and 70 fluid pressure flows from the main supply through valve 16 and conduit 47a to cylinder 17a. The piston 48a is moved to the right, plunger 49a engages the vertical arm of bell-crank 40a, which opens exhaust port 26a and closes the 75

5 maintaining inlet valve 34a of press A, and causes opening of that press. The elements of press B are now in final pressing position and the operator turns to press A where she removes the 5 garment which has just been pressed and replaces it with another whereupon control handles 10 and 11 are depressed. The cycle of operations occurs on press A which has just been described in connection with press B.

10 My improved arrangement of the control mechanism combined with my novel arrangement of the pressing beds greatly reduces the work of an operator. Standing in the angle between the two presses she is in the proper position for 15 placing a garment on the bed of either press A or press B. Thus, assume that she has just placed a garment on press A and, without leaving her position, she depressed the controls 10 and 11 and lowered the press head onto the bed. 20 Simultaneously with the lowering of the head of press A, the head of press B opened. She now has another garment in hand and, with just a turn of the body, she is in a position to place the garment on the bed of press B. When this 25 lay has been completed, she depresses controls 14 and 15. This lowers the head of press B and

simultaneously raises the head of press A, and again she turns to press A. The operator in this fashion continues pressing on both machines with a minimum expenditure of time and effort, as she does not have to move about to reach the controls and pressing elements.

What I claim is:

In combination, right and left hand pressing machines associated for tandem operation, each thereof including relatively movable cooperating 10 pressing members narrowing toward one end, said machines being located at an angle to each other with the narrow ends of their pressing members closely adjacent the vertex of said angle, whereby both machines open toward and 15 are controllable by an operator standing within the angle, power operating means for each machine, pressure-producing control means for each power means, and pressure-releasing control means for each power means, the control means 20 for each machine being grouped and located nearer to its narrow than to its wider end, whereby an operator working adjacent the vertex of said angle can operate both groups of controls with minimum effort.
